DISPLAY RACK FOR TIRES AND ACCESSORIES

Nicholas B. Provenzo, Buffalo, N.Y., assignor to Morrison-International Corp., Buffalo, N.Y., a corporation of New York

Filed Dec. 1, 1961, Ser. No. 67,764

Term of patent 7 years

(Cl. D80—10)

FIG. 3

FIG. 1 is an elevational view taken from one side of a display rack for tires and accessories embodying my new design;

FIG. 2 is a top plan view thereof; and

FIG. 3 is a perspective view thereof taken from the top and right of FIG. 1, the top right panel being broken away for convenience of illustration.

The broken hyphen line representation of a sign and tires in FIG. 1 is for purposes of illustration only.

I claim:

The ornamental design for a display rack for tires and accessories, as shown and described.
